UNITED STATES PATENT OFFICE

104,701

DESIGN FOR A BOILER JACKET

Gilbert Rohde, New York, N. Y., assignor to
Lycoming Manufacturing Company, Williams-
port, Pa., a corporation of Pennsylvania

Application April 12, 1937, Serial No. 68,678

Term of patent 7 years

To all whom it may concern:

Be it known that I, Gilbert Rohde, a citizen of the United States, residing at New York, in the Borough of Manhattan and State of New York, have invented a new, original, and ornamental Design for a Boiler Jacket, of which the following is a specification, reference being had to the accompanying drawing forming a part thereof.

Figures 1 and 2 of the drawing are perspectives from different angles of a boiler jacket showing my new design.

I claim:

The ornamental design for a boiler jacket, substantially as shown.

GILBERT ROHDE.
